UNITED STATES PATENT OFFICE

2,426,925

BALL HONING DEVICE

Rollo G. Ellis, Royal Oak, Mich., assignor to
Micromatic Hone Corporation, Detroit, Mich.,
a corporation of Michigan.

Application December 10, 1942, Serial No. 468,493

1 Claim. (Cl. 51—161)

1

This invention relates to methods and devices for honing spherical surfaces, and particularly to a method and device for honing the outer surface of a sphere to accurate form and dimension.

The main objects of this invention are: to gyrate a workpiece having a spherical surface within a honing tool; to support the workpiece on the end of an arbor and rotate the workpiece as its axis is revolved on the surface of a cone having its apex in the center of the tool; to drive a shaft having a crank arm which supports an arbor at an angle to the shaft as the arbor is rotated by a pinion secured thereto which is in mesh relation with a stationary bevel gear disposed coaxially of the shaft; to provide a honing tool with abrasive stones which are movable toward and away from each other with adjusting means for so moving the stones and with means for adjusting the tool about its vertical axis; to provide a method of honing a spherical surface which embodies the engagement of the surface with stones of a honing tool which are disposed parallel to the base of a cone described by the work supporting arbor as it is rotated and revolved by a suitable driving mechanism; and, in general, to provide a method and device for honing spherical surfaces which is simple in construction, positive in operation, and economical of manufacture.

Other objects and features of novelty of this invention will be specifically pointed out or will become apparent when referring, for a better understanding of this invention, to the following description, taken in conjunction with the accompanying drawing, wherein:

Figure 1 is a plan view of a honing device embodying features of this invention;

Fig. 2 is a broken view of the honing device illustrated in Fig. 1, with the honing tool disposed in position to be movable over a workpiece;

Fig. 3 is an enlarged sectional view of the structure illustrated in Fig. 1, taken on the line 3—3 thereof; and

Fig. 4 is an enlarged sectional view of the structure illustrated in Fig. 3, taken on the line 4—4 thereof.

Referring to the figures, the base 10 of the machine supports a pair of slideways 11 upon which a slide 12 is movable toward and from a workpiece 13. The workpiece is herein illustrated as being a hollow truncated spherical element having a pair of flanges 14 on opposite sides of the spherical surface 15 which is to be honed. Upon the slide 12, a body 16 of the honing tool is secured by the elements 17 and 18, which have ar-

2

uate shaped flanges 19 which extend over the projecting feet 21 and 22 of the body portion. A centrally disposed stud 22, on the bottom of the body portion 16, projects into an aperture 23 in the slide 12 and forms a pivot about which the body portion 16 may be swung from the position illustrated in Fig. 2 to that illustrated in Fig. 1. A pair of spaced shoes 24 are supported in the body portion, to which abrasive stones 25 having segmental spherical faces 26 are secured. The rear edges of the shoes 24 are provided with sloping surfaces 27, which are engaged by sloping surfaces 28 on the arms 29 of the yoke 31. The yoke is supported on a threaded stud 32 upon a yoke element 33, through which the stud extends and relative to which it is adjusted by a handwheel 34, which is screwed onto the stud 32. A spring 35 is disposed between the yoke 31 and yoke element 33 for biasing the yoke 31 downwardly when the handwheel 34 is backed off on the thread 32, out of engagement with the yoke element 33.

Apertures 36 and 37 are provided in the slide 12 through which a pin 38 projects for positioning the honing tool in one or the other of its positions, as illustrated in Figs. 1 and 2. Springs 39 engage the shoes 24 and urge them toward the arms 29 for retracting the stones when the yoke 31 is drawn upwardly after a honing operation.

The workpiece 13 is supported on an arbor 41 when secured by the jaws 42 which are movable inwardly and outwardly by a thumb screw 43 on the end of the rod 44 which extends through the arbor. The arbor is supported by a bearing 45 mounted in an angularly disposed boss 46 on a crank 47 on the end of a shaft 48. The shaft is supported by a bearing 49, which projects from an element 51 which is secured to the base 10 by a plurality of bolts 52. The shaft 48 extends through the central aperture of a bevel gear 53 which is secured against rotation by the bearing 49. A beveled pinion 54 is secured to the arbor 41 in meshed relation with the bevel gear 53.

The shaft is rotated by a motor 55, operating through a gear reduction unit 56 which rotates the shaft 48 and therefore the crank 47 to revolve the arbor 41 on the surface of a cone, the apex of which is on the center of the sphere defined by the faces 26 of the stones 25. As the arbor is revolved on the surface of a cone, it is rotated as the pinion 54 revolves about the gear 53 to gyrate the workpiece between the abrasive stones 25 to perform the honing operation.

After the workpiece is clamped by the jaws 42 to the end of the arbor 41, the honing tool is moved 55 toward and over the workpiece when positioned

normal to the arbor, as illustrated in Fig. 2. Thereafter, the honing tool is revolved about the stud 22 to the position illustrated in Fig. 1, where it is secured by the pin 38 when inserted into the aperture 36. This positions the abrasive stones 15 at opposite ends of the spherical surface 15 in a plane normal to the base of the conical surface traced by the arbor when revolved. When the crank arm 47 has been revolved through 180 degrees to the opposite side of the gear 53, the relative position of the stones will have changed so that they will be at the opposite ends of the workpiece.

By backing off the handwheel 34, the spring 35 exerts a downward pressure on the wedge-shaped arms 29 which applies a predetermined inward pressure to the abrasive stones 25 which engage the spherical surface 15 of the workpiece. After the honing operation, the handwheel 34 is screwed down upon the yoke element 33 to withdraw the yoke 31 and arms 29 to permit the springs 39 to move the shoes 24 and stones 25 away from each other out of engagement with the surface. Thereafter the body portion 16 is shifted about the stud 22 to the position illustrated in Fig. 2 normal to the arbor 41, so that it may be moved away from the workpiece. The workpiece may then be removed from the arbor and another workpiece secured thereto.

By rotating and gyrating the workpiece within the honing tool, a more rugged tool may be employed in which large stones are utilized. The larger stones increase the stone life and produce more rapid abrasion and accurate form to the spherical surface. The rotation of the workpiece 30 in its revolution on the surface of the cone presents all the points of the surface to each of the stones, so that the surface will be abraded and

polished in the same manner throughout the spherical area.

What is claimed is:

5 The combination with a honing tool having a pair of oppositely disposed stones, a slide supporting said tool, an arbor in one of its positions being disposed parallel to the direction of movement of said slide and aligned with the central axis of said tool, means on said arbor for supporting a workpiece, means for driving said arbor in rotation, means for causing said arbor to revolve on the surface of a cone as it is driven, with the apex of the cone disposed on the center of the tool, means for adjusting the stones toward and away from the workpiece, and means for adjusting said tool angularly on the slide to have it disposed normal to the movement of the slide so as to move over said workpiece and to be moved angularly thereafter into a position normal to the axis of the cone on the surface of which the arbor revolves.
